CLAIM

The ornamental design for a handle positioner for a hawk, as shown and described.

DESCRIPTION

FIG. 1 is a top, front perspective view of a handle positioner for a hawk showing the new design;

FIG. 2 is a front elevation view thereof;

FIG. 3 is a right side elevational view thereof, a left side elevational view thereof being a mirror image of the right side elevational view; and,

FIG. 4 is a top plan view thereof.

The broken lines showing the hawk plate are for illustrative purposes only and form no part of the claimed design.
